UNITED STATES PATENT OFFICE.

HARRIET BLACKSTONE C. BUTLER, OF BOSTON, MASSACHUSETTS.

DESIGN FOR A BROOCH, PIN, OR SIMILAR ARTICLE.

51,330.

Specification for Design.

Patented Oct. 9, 1917.

Application filed August 31, 1916. Serial No. 117,943. Term of patent 14 years.

To all whom it may concern:

Be it known that I, HARRIET BLACKSTONE C. BUTLER, a citizen of the United States, residing at Boston, in the county of Suffolk and State of Massachusetts, have invented a new and original Design for a Brooch, Pin, or Similar Article, of which the following is a specification, reference being had to the accompanying drawing, forming part thereof.

The figure is a plan view of a brooch showing my new design.

I claim:

The ornamental design for a brooch, pin, or similar article, as shown.

HARRIET BLACKSTONE C. BUTLER.
